DRESSING RACK FOR FOWLS

Filed April 17, 1929

Inventor
Charles W. Williams,

234 J. Stanley Branch

Attorney

UNITED STATES PATENT OFFICE

CHARLES W. WILLIAMS, OF ARVADA, COLORADO

DRESSING RACK FOR FOWLS

Application filed April 17, 1929. Serial No. 355,846.

The present invention relates to improvements in supports and has reference more particularly to a rack for use in dressing fowls.

One of the important objects of the present invention is to provide a device of the above-mentioned character which includes a suspension frame having a cross bar arranged at the upper portion thereof for securing the legs of the fowl spaced apart, means being arranged at the lower portion of the frame whereby the head of the fowl may be held against movement in order to facilitate the plucking of the feathers of the fowl in a quick and easy manner.

A further and important object is to provide a device of the above-mentioned character wherein the lower cross member is adapted for vertical slidable movement on the frame in order to accommodate fowls of different sizes.

A further and important object is to provide a dressing rack of the above-mentioned character wherein the same is of such construction as to permit the parts to be readily and easily adjusted, the device being further simple in construction, inexpensive, strong and durable and further well adapted for the purposes for which it is designed.

Other objects and advantages of the invention will become apparent from the following description when taken in connection with the accompanying drawing.

In the accompanying drawing wherein like reference characters indicate corresponding parts throughout the same;

Figure 1 is a side elevation of the device embodying my invention showing the same in use.

Figure 2 is a transverse section taken approximately on the line 2-2 of Figure 1, looking downwardly; and

Figure 3 is a vertical section taken approximately on the line 3-3 of Figure 1.

In the drawing wherein for the purpose of illustration is shown the preferred embodiment of my invention, the numeral 1 designates generally the frame of my improved dressing rack, said frame being of substantially U-shaped formation and including a

tubular crown portion 2 having the externally threaded downturned end portions 3. Enlarged sockets 5, formed in the upper end of the coupling members 6, are threaded on the lower ends of the portions 3, and threaded in the smaller sockets 7 formed in the lower ends of these coupling members 6 are the elongated tubular rods 8 that constitute the arms of the inverted U-shaped frame. A cap 9 is arranged on the lower end of each tubular rod 8 in a detachable manner.

An eye bolt 10 extends upwardly from the intermediate portion of the crown 2 for suspending the device from any suitable support (not shown).

A cross bar 11 is arranged transversely with respect to the frame 1 and the end portions of the cross bar are formed with suitable openings to accommodate the portions 3, the bottom face of the cross bar being adapted to engage with the upper ends of the couplings 6 and suitable nuts 12 are threaded on the portions 3 for engagement with the upper face of the cross bar whereby to securely support the same on the frame against vertical movement as is obvious from the construction shown in Figures 1 and 3 of the drawing.

The cross bar is cut away at its forward edge and formed in the forward edge of the cross bar 11 are the spaced leg-receiving notches 13, the same being arranged in inner and outer pairs. For the purpose of securing the legs of the fowl in the respective notches, there is provided a pair of vertically swinging latches 14, each being in the form of a flat metallic bar and the outer ends of these latch members are pivotally connected on the cross bar 11 as at 15 and these latch bars are adapted to be disposed against the notched edge of the cross bar. A downwardly extending finger 16 is formed on the inner free end of each latch bar for a purpose to be presently described.

A metallic plate 17 has its inner end portion secured to the bottom face of the central portion of the cross bar 11 and the outer end portion of this plate 17 extends beyond the notched forward edge of the cross bar and terminates in the upstanding flange 18 that 100

is spaced a slight distance from the notched forward edge of the cross bar to accommodate the inner opposed ends of the vertically swinging latches 14.

- 5 The portion of the plate 17 that projects beyond the notched forward edge of the cross bar 11 is formed with a pair of openings to accommodate the downwardly extending fingers 16 whereby to lock the latches in their lowered position across the open forward ends of the notches 13 and in this manner, the legs of the fowl will be securely held in the notched cross bar. If desired, the downwardly projecting fingers 16 may be formed with 10 transverse openings to accommodate removable locking pins that will prevent the casual displacement of the fingers from the perforated plate 17.

The invention further comprehends the 20 provision of a vertically adjustable unit that is arranged for slidable movement on the lower end portions of the rods 8 and this unit includes a cross member 19 that is in the form of a tubular rod, the ends thereof being secured within the leg portions of T-shaped fittings 20 while the head portions of these T-shaped fittings slidably receive the rods 8. A thumb screw 21 is associated with each T-shaped fitting 20 whereby to secure a cross 25 rod 19 in any vertically adjusted position. The caps 9 on the lower ends of the rod will prevent the displacement of the sliding unit from the frame.

A neck holding clasp 22 is secured on the 30 intermediate portion of the cross rod 19 and extending downwardly from the intermediate portion of this cross rod is the eye bolt 23 from which may be suspended a blood bucket 24 to catch the blood as it drains slowly from neck of the fowl.

The use of my improved dressing rack is thought to be readily obvious from the construction disclosed and it will be apparent that when the legs of the fowl are clamped 45 in either the inner or outer pair of notches and the neck of the fowl is engaged with the clasp 22, the fowl will be held in a firm position on the frame so that the feathers of the fowl may be readily plucked.

50 A device of this character will save considerable time and labor and can be used for working upon chickens, ducks, and other fowl as well as game. The simplicity of my device enables the parts to be readily and easily 55 adjusted and the same will at all times be positive and efficient in carrying out the purposes for which it is designed.

While I have shown the preferred embodiment of my invention, it is to be understood 60 that minor changes in the size, shape and arrangement of parts may be resorted to without departing from the spirit of the invention or the scope of the appended claims.

What I claim is:

- 65 1. In a suspension device for fowls, a sup-

port, a horizontally disposed bar mounted on the support and formed with leg-receiving notches in one edge thereof, a pair of latch members pivotally secured at their outer ends to the bar and adapted for swinging movement across the notched edge of said bar, a plate secured on one face of the bar and extending outwardly therefrom, the outwardly extending portion of the plate being formed with openings, and laterally extending fingers formed on the inner ends of the latches for disposition through the respective openings to maintain the latches in a lowered position across the notches in the bar.

2. In a device of the class described, a substantially inverted U-shaped frame, means carried by the crown portion thereof for suspending the frame from a support, a cross bar arranged transversely across the upper portion of the frame and provided with means for receiving and supporting the legs of a fowl, an additional cross bar, means carried by said last-mentioned cross bar for slidable movement on the lower ends of the arms of the U-shaped frame, means for securing the last-mentioned cross bar in any vertically adjusted position, and neck-engaging means carried by the intermediate portion of the 85 90 95 100 105 110 115 120 125 130

3. In a device of the class described, a substantially inverted U-shaped frame, means carried by the crown portion thereof for suspending the frame from a support, a cross bar arranged transversely across the upper portion of the frame and provided with means for receiving and supporting the legs of a fowl, an additional cross bar, means carried by said last-mentioned cross bar for slidable movement on the lower ends of the arms of the U-shaped frame, means for securing the last-mentioned cross bar in any vertically adjusted position, and neck-engaging means carried by the intermediate portion of the 100 105 110 115 120 125 130

In testimony whereof I affix my signature,
CHARLES W. WILLIAMS.
